K. LUND.
RUDDER LOCK.
APPLICATION FILED FEB. 5, 1913.

1,080,641.

Patented Dec. 9, 1913.

Inventor:

Kield Lund,

Jas. E. Hutchinson.
G. A. Marvin.

By Royal E. Burnham, Attorney.

UNITED STATES PATENT OFFICE.

KJELD LUND, OF SOUTHPORT, NORTH CAROLINA.

RUDDER-LOCK.

1,080,641.

Specification of Letters Patent.

Patented Dec. 9, 1913.

Application filed February 5, 1913. Serial No. 746,338.

To all whom it may concern:

Be it known that I, KJELD LUND, a citizen of the United States, residing at Southport, in the county of Brunswick and State 5 of North Carolina, have invented certain new and useful Improvements in Rudder-Locks, of which the following is a specification, reference being had therein to the accompanying drawing.

10 This invention provides a quickly-acting and reliable means whereby a ship's rudder is held in fixed position in case the steering-gear is accidentally put out of operation by breaking or otherwise, so that repairs may 15 be made.

Through the breaking of steering-gear or tiller-ropes many ships have been wrecked and lives and property lost. When such an accident occurs in a heavy sea, the tiller 20 or quadrant oscillates with violence from one side to the other and further injury sustained by the steering mechanism, and these conditions are particularly disastrous when 25 a vessel is close to a lee shore. It is a comparatively easy matter to make repairs when the motion of the rudder and associated parts can be stopped, and this invention provides a device for locking the rudder in fixed 30 position while repairs can be made, the mechanism being easily thrown into locking position by means accessible from the deck of a vessel.

When read in connection with the description herein, the details of construction and 35 arrangement of parts contemplated by this invention will be apparent from the accompanying drawing, forming part hereof, wherein an embodiment of the invention is disclosed, for purposes of illustration.

40 While the disclosures herein now are considered to represent the best embodiment of the invention, it is to be understood that they merely are illustrative of the principles thereof, that the several instrumentalities 45 employed in carrying out the invention can be variously organized within the limits prescribed by the claims hereinafter without departing from the nature and spirit of the invention, and that it is not the intention 50 to be limited necessarily to the precise delineation herein in interpretation of the claims.

Like reference-characters refer to corresponding parts in the views of the drawing, 55 of which—

Figure 1 is a side view of the stern por-

tion of a vessel having my invention associated therewith, a part of the hull being broken away for a disclosure of the invention; Fig. 2 is a plan view of the locking mechanism; Fig. 3 is a view of the steering-sector; Fig. 4 is a side view of the stopper-block; Fig. 5 is a rear view of the stopper-block; and Fig. 6 is a sectional view of the operating-stand.

Having more particular reference to the drawing, 6 designates a vessel, 7 the rudder, and 8 the rudder-post thereof extending to the deck of the vessel. A sector or other suitable member 9, which may be a quadrant of somewhat the usual form, to which force is applied, by means of tiller-chains 10 or otherwise, is fixedly secured to the rudder-post above the deck, whereby the requisite movements for steering the vessel are 75 imparted to the rudder. The under side of the sector is comparatively smooth and capable of sliding contact with a part yet to be described.

Supports 11 and 12 are secured to any 80 suitable fixed parts, as to the under side of the deck. A slide 13 is held by these supports, a single end being held by support 11 and the other end being forked or bifurcated and extending on each side of the rudder-post and held by supports 12. Intermediate its ends the slide is formed with a yoke 14, in which is disposed an eccentric 85 15. The eccentric is on a rod or shaft 16 extending to a stand 17 or to any other easily-accessible position on the deck of the vessel, and on this rod is a crank or handle 18, for the purpose of turning the rod and eccentric and imparting longitudinal movement to the 90 slide.

In supports 19 secured to the under side 95 of the deck or to other suitable fixed parts is supported on trunnions 20 an arm or lever 21 formed with weighted portions 22 on one side of the trunnions and a single member 23 on the other side, and on the weighted portions is a cross-bar or member 24, which normally rests on the ends of the bifurcated portions of the slide 13, whereby the said weighted portions of the arm 21 normally 100 are held in raised position. A plate 25 is set in the deck, preferably amidship, under the sector 9 on the rudder-post, and in this plate is a vertically-movable stopper-block or key 26 arranged to be moved to bring its upper 110 portion into contact with the under side of the sector and into engagement with an

aperture 27 in the sector, this aperture preferably being located so that it will be amidship and directly over the stopper-block when the rudder is amidship. The lower 5 portion of the stopper-block is formed with a slot 28 having its upper end rounded as shown, and in this slot, and held therein by a bolt 29, is disposed the portion 23 of the lever 21, this portion being curved down- 10 wardly to facilitate movement of the parts to the position shown by dotted lines in Fig. 1. It will be seen that the bolt 29 and the portion 23 will prevent the stopper-block from jumping out of the plate and being 15 lost.

In order to maintain the slide normally in position to keep the weighted portions of the lever raised and the stopper-block out of operative position, the crank 18 may be 20 hinged intermediate its ends, as shown at 30, so that a knob or the like 31 on the end thereof may be turned over into a socket 32 in the top of the stand 17.

When the parts are in their normal positions, as shown by full lines in Fig. 1, the stopper-block is in depressed position and out of engagement with the aperture in the sector. When it is desired for any reason to lock the rudder, the knob 31 of the handle 30 18 is withdrawn from the socket 32 and the hinged portion of the handle turned over until it assumes an extended position. Then the handle is manipulated to turn the eccentric 15 and withdraw the slide from 35 position of supporting contact with the weighted end of the lever. Thereupon, that end of the lever will drop and raise the other end. On this movement, the stopper-block will be forced into the aperture 27 40 and the rudder locked, if at that time the rudder is amidship. Otherwise, the stopper-block will be forced against and have sliding contact with the under side of the sector, and when the aperture, during swinging of 45 the rudder, comes amidship, the weighted lever then will force the block into the aperture and the rudder will be locked.

It will be seen that the handle 18 is in a 50 position for easy and quick access in case of emergency, so that the device can be thrown into locking position without delay.

If desired, the device may have associated

with it electric or other means for operation from the bridge or pilot-house.

Having thus described my invention, what 55 I claim as new, and desire to secure by Letters Patent, is—

1. The combination of a rudder, a sector connected therewith and having an aperture therein, a stopper-block below the sector capable of movement to locking position of contact with the under side of the sector and into engagement with the aperture thereof, a lever in engagement with said stopper-block and movable to raise the latter to locking position, a slide normally in engagement with said lever and holding the lever and stopper-block out of locking position, and means whereby said slide is moved from locking position with respect to said lever. 70

2. The combination of a rudder, a sector connected therewith and having an aperture therein, a stopper-block below the sector capable of movement to locking position of contact with the under side of the sector 75 and into engagement with the aperture thereof, a weighted lever in engagement with said stopper-block and operable to raise the latter to locking position, a slide normally in engagement with said lever and holding the 80 lever and stopper-block out of operation, said slide comprising a yoke, and an eccentric in said yoke.

3. The combination of a rudder, a sector connected therewith and having an aperture 85 therein, a vertically-movable stopper-block below the sector capable of movement to locking position of contact by its upper end with the under side of said sector and into engagement with the aperture thereof and 90 having in its lower end a slot, a lever having an end disposed in the slot of said stopper-block and operable to raise the stopper-block to locking position, and means normally retaining said lever in inoperative position 95 and operable to release said lever and permit said stopper-block to be moved to locking position.

In testimony whereof I affix my signature in presence of two witnesses.

KJELD LUND.
